UNITED STATES PATENT OFFICE.

JULIUS EMMNER, JR., OF WASHINGTON, DISTRICT OF COLUMBIA, ASSIGNOR
OF ONE-HALF TO JOSEPH A. SETTLE, OF SAME PLACE.

DYNAMO-ELECTRIC MACHINE.

SPECIFICATION forming part of Letters Patent No. 390,955, dated October 9, 1888.

Application filed April 18, 1888. Serial No. 271,007. (No model.)

To all whom it may concern:

Be it known that I, JULIUS EMMNER, Jr., a citizen of the United States, residing at Washington, in the District of Columbia, have invented certain new and useful Improvements in Armatures for Dynamo-Electric Machines and Motors; and I do hereby declare the following to be a full, clear, and exact description of the invention, such as will enable others skilled in the art to which it appertains to make and use the same.

This invention relates to dynamo-electric machines. The object is to produce a ring or cylindrical armature for dynamo-electric machines so constructed that the coils may readily and rapidly be removed, when desired, for the purpose of replacing them, when worn or injured by accident or otherwise, with others, and by displacing but few parts. Furthermore, the object is to produce a ring or cylindrical armature so formed that any particular coil may be removed without displacing any other coil or any other section of the ring than that to which the particular coil is attached; and, finally, the object of the invention is to produce a ring or cylindrical armature for a dynamo-electric machine of such construction that all the parts shall easily be accessible to air, in order that they may be prevented from becoming heated, &c.

With these objects in view the invention consists in a ring or cylindrical armature comprising a drum, a series of sections provided on one side with a tongue or projection and on the other side with a groove entered by the tongue of the adjacent section and detachably connected thereto, the grooves in the sections extending to one of the edges of the sections, in order that any one section may be removed without displacing the adjacent sections.

Furthermore, the invention resides in a ring-armature comprising a suitable drum and a series of ring-sections so formed that when joined they shall make a complete ring of such shape as to allow a free circulation of air.

Furthermore, the invention consists in a ring or cylinder armature comprising a drum and a series of removable ring-sections having connecting tongues or projections and retaining them a short distance from the surface of the drum; and, finally, the invention consists in

various novel details of construction whereby the objects of the invention are attained and the effectiveness of the invention is insured.

I have illustrated the invention in the accompanying drawings, in which—

Figure 1 is a perspective view of a ring armature made in accordance with my invention. Fig. 2 is an end elevation of the armature. Fig. 3 is a sectional view of one of the rib sections, the tongue or connection being shown broken away. Fig. 4 is a detail perspective view showing the side plate of the ring-section to which the tongue is attached. Fig. 5 is a detail perspective view of the plate forming the side of the ring-section opposite to that upon which the tongue is attached or formed, showing the groove entered by the tongue of the adjacent section. Fig. 6 is a perspective view of the sleeve upon which the wire is wound, it being shown as composed of strips secured together and with interposed insulating strips. Fig. 7 is a perspective view of a sleeve made of layers separated by insulating material, and Fig. 8 is a view showing a modified form of ring-section.

In the drawings, the letter A designates a drum, made of brass or other non-magnetic metal, keyed or otherwise permanently attached to a shaft through which the drum receives motion. Secured to the periphery of this drum is a series of sections, B, attached to the drum by suitable screws or bolts, b, passing through the sections and entering the drum a suitable distance to hold them securely in place. The sections B are composed of a series of plates, b', the outer plates on one side of each of the sections being provided with a projecting tongue, b'', of a breadth somewhat less than that of the plate to which it is attached or with which it is formed. The plate on the opposite side of the section is formed with a groove or slot, b'', extending to one end of the plate, and is entered by the tongue of the adjacent section. The portion of the sections between the outer plates is composed of

plates of soft iron, insulated from each other by any suitable material and held in place by retaining bolts or screws.

Between the sections B of the armature, and supported by the projections or tongues thereof, are the sleeves C, each composed of a number

of strips, bands, or layers of metal insulated from each other. Upon these sleeves are wound the wires c' , as shown in Fig. 2 of the drawings.

- 5 In Fig. 6 of the drawings I have shown the sleeve as composed of a series of strips or bands insulated from each other, while in Fig. 7 I have shown the sleeve as composed of a series of insulated layers of metal. These two 10 constructions are considered equivalents of each other.

In Fig. 8 of the drawings I have shown a modified form of the ring-section. In this form the side plates bearing the tongue and 15 groove, respectively, are connected at their lower ends by a plate, c , which has an opening to receive a screw passed through the drum for the purpose of securing the section thereto. By the employment of this form the necessity 20 of passing the retaining-screw completely through the section is obviated.

Having thus fully described my invention, what I claim as new, and desire to secure by Letters Patent, is—

- 25 1. An armature for dynamo-electric machines, comprising a drum, a series of ring-sections attached thereto and provided on one side with a tongue and on the other with a groove, and coils placed on the tongues, substantially as described.
- 30 2. An armature for dynamo-electric machines, comprising a drum, a series of ring-sections provided on one side with a tongue and on the other with a groove extending to the 35 end and attached to the drum, and coils placed upon the tongues, substantially as described.

3. An armature for dynamo-electric machines, comprising a drum and a series of ring-sections attached to the drum, made up of metal plates insulated from each other, the said sections being provided with tongues on one side and with grooves on the other, substantially as specified and described.

4. An armature for dynamo-electric machines, comprising a drum, a series of ring-sections, each provided on one side with a tongue and on the other with a groove, and the sleeves composed of a series of strips, layers, or bands of metal insulated and having the wire wound thereon, the said sleeves being placed on the 50 tongue, substantially as described.

5. An armature for dynamo-electric machines, comprising a drum, a series of ring-sections attached thereto, made up of plates insulated from each other, the said sections being provided with interlocking tongues and 55 grooves, and the sleeves composed of insulated strips, bands, or layers placed upon the tongues and carrying the wire.

6. An armature for dynamo-electric machines, comprising a drum and a series of ring-sections attached thereto, each section being provided with a tongue and with a groove extending to the edge, substantially as described.

In testimony whereof I affix my signature in 65 presence of two witnesses.

JULIUS EMMNER, JR.
